D7-343

EX

OR D 12,255

Design No. 12,255, dated May 10, 1881.

UNITED STATES PATENT OFFICE.

THOMAS J. MARCH, OF LIMERICK STATION, PENNSYLVANIA.

DESIGN FOR COOKING-STOVE.

SPECIFICATION forming part of Design No. 12,255, dated May 10, 1881.

Application filed August 9, 1880. Term of patent 7 years.

To all whom it may concern:

Be it known that I, THOMAS J. MARCH, a citizen of the United States, residing at Limerick Station, in the county of Montgomery and State of Pennsylvania, have invented and produced a new and Original Design for the Ornamentation of Stoves or Ranges, of which the following is a specification, reference being had to the accompanying drawing, forming part thereof.

Said drawing represents a perspective view of a cooking-stove provided with the invention.

The panel of the oven-door is provided with a scene in which a miner, A, is represented, provided with mining implements B and surrounded by coal C. The panels of the remaining stove-doors are respectively provided with a scene representing a number of mining implements bunched together at their middle portions.

It is evident that the mere location of these scenes does not constitute an essential part of the invention.

Preferably I provide the oven-doors with the

scene of the miner, and the other doors with the scene of the mining implements, as illustrated in the drawing.

Either one of said scenes may be represented without the other, and any suitable portion of the stove or range may be used as the location for their representation.

Having fully described my invention, what I claim as new, and desire to secure by Design Patent, is—

1. A design for a panel of a stove, substantially as shown on the oven-door.
2. A design for the ornamentation of a stove or range door or plate, consisting of the representation of mining implements, substantially as described and shown.

3. A design for stoves representing the miner, substantially as described, on one panel, and mining implements on other panels, substantially as described.

THOMAS J. MARCH.
